UNITED STATES PATENT OFFICE.

FRANK HOF, OF NEW YORK, N. Y.

HARNESS-HANGER.

No. 873,549.

Specification of Letters Patent.

Patented Dec. 10, 1907.

Application filed May 29, 1907. Serial No. 376,257.

To all whom it may concern:

Be it known that I, FRANK Hof, a citizen of the United States, and a resident of the city of New York, borough of the Bronx, in 5 the county and State of New York, have invented a new and useful Improvement in Harness-Hangers, of which the following is a full, clear, and exact description.

The invention relates to devices for holding harness in suspension in engine houses, truck houses, and the like, and the purpose of the invention is to provide a single piece hanger and a rocker for the hanger, adapted both as a rest and a release for parts of a 15 harness, the hanger and accompanying rocker being so constructed that the breeching of the harness will be supported by the rear portion of the hanger and the hames and reins by the said rocker, which is located at 20 the forward portion of the hanger.

It is a further purpose of the invention to so construct the device that it will be simple and economic, and reliable in operation, and so that by drawing down upon the reins the 25 entire harness will be instantly and automatically released from the hanger.

The invention consists in the novel construction and combination of the several parts, as will be hereinafter fully set forth 30 and pointed out in the claims.

Reference is to be had to the accompanying drawings forming a part of this specification, in which similar characters of reference indicate corresponding parts in both the 35 figures.

Figure 1 is a perspective view of the hanger and a harness supported thereby; and Fig. 2 is an enlarged longitudinal section through the forward portion of the hanger and a side 40 elevation of the rocker, illustrating its rests in supporting position in positive lines and in discharge position in dotted lines.

A represents the body bar of the hanger, and B a cross bar located at the rear of the 45 body bar and at right angles thereto, and these bars are each in one piece, and are made tubular in the interest of lightness. The cross bar B may be attached to the body bar A in any approved manner, usually, 50 however, a T-fitting 10 is employed for the purpose, and the forward end of the body bar A and each end of the cross bar B is upwardly curved, and said ends terminate in balls 11, so that when the hanger is carried

upward after the harness is released therefrom, the ends of the hanger will not mar the ceiling or overhead support. A post 12 extends up from the body bar A between its ends, which post is shown located at or near the center, and may be an integral portion of 60 the body bar, but is shown secured to the said body bar by a sleeve 13, the sleeve and post in such an event being integral parts. The post 12 is provided with an eye 14 at its upper end, and a suspension rope or cable 15 65 is secured to the post at the said eye, and adjacent the eye the suspension cable 15 is provided with an attached ball or other form of offset 16, whereby to limit the upward movement of the cable when the harness is released from the hanger, the cable being provided with the usual attachment weight or weights.

The hanger is braced by means of truss rods 17, which are in the form of bars, and 75 are secured to opposite sides of the upper end portion of the suspension post 12, and at their outer ends the said truss rods or bars 17 are secured to the body bar A by means of clips 18, or their equivalents. The truss 80 rods or bars 17 extend nearly from the said suspension post to the ends of the body bar, but the forward truss rod or bar 17 is further removed from the forward end of the said body bar than is the rear truss rod or bar from the 85 rear end of said body bar. A weight 19 is attached to, or is formed around a part of the body bar A between the forward clip 18 and the forward end of the body bar, and this weight 19 is adapted to counterbalance the 90 hanger as an entirety and maintain it when elevated in a substantially horizontal position. In front of the weight 19 yet back of the forward end of the body bar of the hanger, a slot 20 is produced in the upper 95 surface of the said body bar, and a longer and corresponding slot 21 is produced in the under face of the said body bar, as is best shown in Fig. 2.

At the slotted portion of the body bar A, a 100 rocker C is mounted in the body bar. This rocker is usually constructed as illustrated, wherein it consists of a disk body 22, through the center of which a pivot pin 23 is passed, the pin likewise passing through the body 105 bar below the central portion of the upper slot 20 therein, as is also best shown in Fig. 2. Two rest members 24 and 25 extend from

the lower peripheral portion of the disk body 22, and these rests 24 and 25 are located one above the other and are by preference given the hook formation illustrated, the curvature of both rests 24 and 25 being upward to a greater or lesser extent, and by preference the lower rest 25 is larger than the upper one 24, and when the rocker C is in locking position, shown in positive lines in Fig. 2, the 10 outer end of the upper rest 24 enters the body bar A through the lower slot 21 therein, and the lower rest 25 occupies such a position that its vertical center is practically in vertical alinement with the center of the pivot 15 pin 23.

Rearwardly extending hooks 26, or their equivalents, are secured to the cross bar B adjacent its ends, as is shown in Fig. 1, and these rear hooks 26 are adapted to receive 20 rings 27 attached to the breeching section D of the harness, and in applying the harness the center ring 28 of the hame D' is passed over the lower rest 25, while the snap 29 of a rein D² passed through the said ring 28 is 25 made to engage with the upper rest 24. The weight of the forward portion of the harness upon the lower rest of the rocker C will bring the said rests to their normal position, carrying the free end of the upper rest into the said 30 body bar, as is shown in both Figs. 1 and 2. When the harness is to be released from the hanger the man at the head of the horse will simply grip the suspended rein D² and draw it downward. In so doing the rocker C will 35 be moved so that both of its rests are carried to the discharge position shown in dotted lines in Fig. 2, and immediately the hame and the rein will leave the rocker and the rear end portion of the hanger will incline 40 downward, releasing the breeching of the harness, which will drop upon the animal, while the hanger will be carried upward out of the way in the customary manner.

Having thus described my invention, I 45 claim as new and desire to secure by Letters Patent,—

1. In a hanger for suspending a harness, a body bar having a slotted portion, and a rocker having a body pivoted in the slotted 50 portion of the body bar and provided with rest members extending from the body, the end of one of said rest members being adapted to enter the slotted portion of the body bar.

55. 2. In a hanger for suspending harness, a tubular body bar having slots produced in its upper and lower surfaces adjacent to one end thereof, a rocker having a body mounted to turn in the slotted portion of the body bar, 60 and rest members extending from the lower portion of the rocker body and located one above the other, the outer end of the upper rest member being adapted to enter the slot in the lower face of the body bar.

3. In a hanger for suspending a harness, a 65 body bar having a slotted forward portion, a cross bar attached to the body bar, means carried by the cross bar for supporting the breeching section of a harness, and a rocker comprising a disk body pivoted in the slotted 70 forward portion of the body bar, said disk body having an upper and a lower hook-shaped member extending from its lower peripheral portion and forming rests for parts of the forward portion of a harness, the 75 end of the upper hook-shaped member being adapted to enter the slotted portion of the body bar.

4. In a hanger for suspending a harness, a body bar having slots in the upper and lower 80 surfaces thereof at its forward portion, a cross bar attached to the body bar, means carried by the cross bar for supporting the breeching portion of a harness, a rocker pivoted in the slotted forward portion of the 85 body bar, which rocker is provided with hook-shaped rests, one below the other, the upper rest being adapted to receive the snap of a rein and the lower rest the ring of the hame through which the rein passes, the said 90 upper rest, when the rocker is in locking position, entering the lower slot in the body bar.

5. In a hanger for suspending a harness, a body bar, and a rocker comprising a body 95 pivoted to the body bar, and hook-shaped rests extending from the pivoted body, one below the other, the free end of the upper rest when in closed position engaging an opening in the body bar, the said rests being 100 carried to closed position by the weight of the harness and brought to discharge position by the withdrawal of a portion of the harness.

6. In a hanger for suspending a harness, 105 the combination with a body bar in one piece, a cross bar in one piece secured to the end of the body bar, the forward end of the body bar and the ends of the cross bar being upwardly curved and having rounded terminal portions, a suspension member extending from the body bar, truss members extending from the suspension member to an engagement with the body bar at opposite sides of its center, and a counterbalancing 110 weight at the forward end of the body bar, of a rocker pivotally mounted in the forward end of the body bar, said rocker being provided with open rests for the reception of parts of the forward pieces of a harness, and 115 means carried by the cross bar of the hanger for temporarily supporting the pieces of the harness at the rear thereof.

7. In a hanger for suspending a harness, a tubular body bar having registering slots 125 in the upper and lower surfaces near one end thereof, the slot in the under surface being longer than the slot in the upper surface, a

rocker comprising a disk body extending through the slots in the body bar, a pivot pin extending through the center of the disk body and through the body bar below the 5 central portion of the upper slot, and hook shaped rests extending from the lower peripheral portion of the disk body and located one above the other, the outer end of the upper rest, when the rocker is in locking posi-

tion, entering the body bar through the 10 lower slot.

In testimony whereof I have signed my name to this specification in the presence of two subscribing witnesses.

FRANK HOF.
